2,134,980

WASHING MACHINE DRIVING MECHANISM

John Mikulasek, Newton, Iowa, assignor to The Maytag Company, Newton, Iowa, a corporation of Delaware

Original application May 14, 1932, Serial No. 611,279. Divided and this application November 29, 1935, Serial No. 52,080

15 Claims. (Cl. 74—75)

The present invention relates to washing machines, and more in particular to a novel means and method of operating the agitator or impeller, and wringer drive shaft of a washing machine.

5 This application is a division of my co-pending application Serial No. 611,279, filed May 14, 1932.

Among the objects of the present invention is the provision of a novel means and method of operating the agitator or impeller so as to give it 10 a rapid oscillatory or reciprocatory movement in the tub for vigorously impelling the washing fluid in gyratory or circuitous paths. In the preferred embodiment, the agitator or impeller is oscillated through an arc less than a complete revolution, although it is to be understood that such impeller or agitator may oscillate in an arc of any desired amplitude to secure an efficient washing 15 operation.

A further object of the invention is the provision of a novel means and mechanism for driving and rapidly oscillating and reciprocating the agitator or impeller in order to secure the desired washing operation. In actual practice, I have found that approximately fifty to sixty oscillations or complete reversals per minute are desirable for setting up a violent water action.

A still further object of the invention is the provision of a novel drive mechanism for a washing machine for simultaneously driving or operating the wringer and agitator shaft, and when desired, permitting a declutching of the agitator shaft whereby the wringer shaft alone may be driven.

Another object of the invention is the provision of a novel clutch mechanism associated with the drive means and agitator shaft for selectively connecting or disconnecting said shaft from the drive means.

Further objects are to provide a construction 40 of maximum simplicity, efficiency, and ease of assembly and operation, and such further objects, advantages and capabilities as will later more fully appear, and as are inherently possessed thereby.

45 The invention further resides in the combination, construction and arrangements of parts illustrated in the accompanying drawings, and while there is shown therein a preferred embodiment, it is to be understood that the same is susceptible of modification and change, and comprehends other details, arrangements of parts, features and constructions, without departing from the spirit of the invention.

In the drawings:
55 Fig. 1 is a view, part in side elevation and part

in vertical cross section of the washing machine and its drive mechanism.

Fig. 2 is a fragmentary enlarged view in vertical cross section taken through the tub, agitator or impeller and the drive mechanism.

Fig. 3 is a cross sectional view taken in a plane represented by the line 3—3 of Fig. 2.

Fig. 4 is a plan view of the clutch plate.

Fig. 5 is a plan view of an alternate construction of drive mechanism for oscillating or reciprocating the agitator or impeller.

Referring more particularly to the disclosure in the drawings, the novel drive mechanism is shown as mounted upon a washing machine having a tub 1 provided with a concaved bottom 2 and side walls 3 forming a substantially uninterrupted continuous surface. The tub is shown as provided with a skirt or housing 4 having supporting legs 5 and casters 6 permitting the machine to be readily moved about. The drive mechanism is shown as housed in a casing 7 mounted adjacent the bottom of the tub and to one side thereof. This drive mechanism is adapted to rapidly oscillate an agitator or impeller 8 as well as operate the wringer 9, the latter being provided with a drive head 10 mounted upon a standard 11 having its upper bearing in a bracket 12 mounted upon the tub, and its lower bearing in a boss 13 formed or provided in the top of the casing or housing 7.

30 The agitator or impeller 8 may be of any suitable construction with the base 14 thereof either dished or flat and provided with one or more blades or vanes 15 for impelling the washing fluid. A bead 16 is mounted in the tub to encompass the outer edge or periphery of the impeller or agitator and lie in close proximity thereto so as to prevent the clothes or other materials being washed from finding access under the impeller or agitator. To permit a complete and rapid emptying of the washing or cleansing fluid from the tub, the lowermost portion thereof is shown as perforated, and located below the same is a drain or sediment trap 17 leading to a drain hose 18. A lid 19 forms a closure for the top of the tub.

35 In the disclosed embodiment, the novel means for driving the agitator and wringer comprises a motor or other power plant 20 having a drive shaft 21 upon which is mounted a pulley 22 driving a belt 23 and which in turn rotates a pulley 24 upon a shaft 25, this latter shaft passing into the housing or casing 7 and driving a worm 26 suitably keyed or fixed thereto. This worm is in constant mesh with a worm gear or wheel 27.

30

of a gear member, the latter having a bevel gear or pinion 28 in meshing engagement with a bevel gear or pinion 29 fixed on the wringer drive shaft 30. This wringer drive shaft is shown as 5 coupled to an aligned shaft 31 by means of a coupling member 32. From the above description it will be readily seen that worm 26, worm wheel or gear 27, and bevel gears 28 and 29 are continuously rotated at all times that the motor 10 or power plant is being operated.

In order to oscillate or reciprocate the impeller or agitator 8, the worm wheel 27 and bevel gear 28 rotate upon a sleeve or bushing 33 encompassing the agitator or impeller shaft 34, the latter being rotatable within this sleeve or bushing. 15 In order to take care of any end thrust and prevent shifting of the gear member making up the worm wheel or gear 27 and gear or pinion 28, the sleeve or bushing 33 is provided with a shoulder 20 35 against which this member seats. A clutch member 36 is also rotatable upon the sleeve 33 as well as slideable thereon and is provided with one or more upwardly or outwardly projecting pins 37 suitably mounted thereon and extending 25 through the gears 27 and 28 so that these gears and the clutch member rotate together as a unit.

In Figs. 1 and 2 the clutch member 36 is disclosed as in raised or clutching position whereby the gears 27 and 28 and the clutching member 30 may be in contacting engagement, and the pin 37 30 is raised into a position where it engages in an opening 38 in a clutch plate 39. Mounted upon this clutch plate is an eccentric 40 provided with a strap or collar 41 connected to a pitman arm 42. The clutch plate 39, eccentric disc 40 and collar or strap 41 are also rotatably mounted upon the sleeve 33.

This clutch member 36 is provided with an annular groove 43 in which is seated a bifurcated 40 clutch arm 44 pivotally mounted upon a shaft or rod 45, the latter being adapted to be rotated and the arm shifted by means of a clutch handle 46 conveniently mounted on the exterior of the tub or machine. In order to communicate the oscillating or reciprocating movements of the eccentric disc 40 to the shaft 34, the arm 42 is fulcrumed at 47 to a cantilever 48, one end of which is pivotally mounted upon a stub shaft 49, and the opposite end connected to a link 50 and arm 51 keyed or fixed to the agitator or impeller shaft 34. By reason of this arm and link construction, the continuous rotation of the worm gear or wheel 27 communicated to the eccentric disc 40 50 by reason of the clutch member 36 and clutching plate 39, is changed to an oscillatory or reciprocating movement imparted to the shaft 34 and the impeller or agitator 8.

The shaft 34 is disclosed as bearing in the sleeve 33 and likewise in a sleeve 52 provided in the upper portion of the casing or housing 1. Ad- 60 jacent its upper end, the shaft 34 is suitably keyed to a splined-torque-head 53 upon which is mounted the impeller or agitator. The coupling of the agitator or impeller to the shaft and the torque-head may be made in any suitable manner 65 but preferably permitting a ready detachment and replacement of the agitator or impeller.

In order to prevent seepage or leakage of the washing fluid from the tub, there is provided a 70 packing 55 seating against a spring 56 on the top of the casing or housing 1, and at its upper edge threaded to a sleeve 51 having a lower annular flange 58 adapted to seat against the exterior of the tub. This sleeve 51 is also 75 threaded exteriorly to receive a cap 59 adapted to

seat against the interior of the tub and to draw the flange 58 of the sleeve 51 into seating engagement with the exterior of the tub. This cap is provided with an annular opening in which is seated a packing or washer 60 and by reason of 5 this construction an efficient liquidtight seal is provided.

In Fig. 5 is disclosed an alternate construction of drive mechanism for the impeller or agitator in which the arm 42 of the eccentric 40 is connected at 61 to a gear segment 62 pivotally mounted on a stub shaft 63. This segment is reciprocated or oscillated by the eccentric and in turn meshes with a pinion 64 suitably keyed or fixed on the agitator shaft 34 and imparts an 15 oscillatory or reciprocatory movement to the shaft 34 and the agitator or impeller.

From the above description and the disclosure in the drawings, it will be readily seen and appreciated that the invention comprises a novel means 20 and method of operating the agitator or impeller of a washing machine, as well as the wringer drive.

Having thus disclosed the invention,

I claim:

1. In a gearing for washing machines provided with a tub, an oscillating shaft extending into said tub, drive means on said oscillating shaft, a constantly driven shaft driven by said drive means, an eccentric for oscillating the shaft and 30 clutch means for connecting and disconnecting said drive means and eccentric.

2. In a gearing for washing machines provided with a tub, a housing positioned at one side of said tub, an oscillating shaft having a bearing in 35 said housing and extending into said tub, drive means on said oscillating shaft, a constantly driven shaft also having a bearing in said housing and driven by said drive means, an eccentric for oscillating the shaft and clutch means for 40 connecting and disconnecting said drive means and eccentric.

3. In an operating mechanism for the agitator and wringer shaft of a washing machine, comprising a continuously rotating drive means on 45 the agitator shaft, a drive pinion on said wringer shaft in constant meshing engagement with said drive means, an eccentric for oscillating said agitator shaft, and clutch means for connecting and disconnecting said drive means and eccentric.

4. In gearing for washing machines, in combination, an oscillating agitator shaft, a constantly driven wringer shaft, driving means for said shafts comprising a worm and a worm wheel and pinion loose on said agitator shaft, a pinion fixed on said wringer shaft in constant mesh with said first mentioned pinion, an eccentric for oscillating the agitator shaft, and clutch means for 55 connecting said worm wheel and eccentric to the agitator shaft for rapidly oscillating the same.

5. In gearing mechanism for operating a washing machine, in combination, an oscillating shaft, a constantly driven shaft, an eccentric member loosely mounted on said oscillating shaft, continuously rotated gearing on said oscillating shaft, 65 adapted to drive said constantly driven shaft, clutch means for connecting said gearing and eccentric, and means connecting the eccentric and oscillating shaft for oscillating said last mentioned shaft.

6. Mechanism for operating the agitator and wringer shaft of a washing machine, comprising in combination, an agitator shaft, a wringer shaft, and means on said agitator shaft for oscillating said agitator shaft and for continuously 75

- rotating said wringer shaft, said means including a continuously rotating drive member, an eccentric loosely mounted on said agitator shaft, clutch means adapted to form a clutching engagement 5 with said drive member and eccentric, and means connecting said eccentric and agitator shaft for oscillating said shaft.
7. Mechanism for operating the agitator and wringer shaft of a washing machine, comprising 10 in combination an agitator shaft, a wringer shaft, a pinion on said wringer shaft, means on said agitator shaft for oscillating said agitator shaft and for continuously rotating said wringer shaft, said means including a continuously rotating 15 drive gear, a pinion on said drive gear meshing with and rotating the pinion on said wringer shaft, an eccentric loose on said agitator shaft, a clutch also loose on the agitator shaft, and means for connecting said clutch, gear and eccentric to said agitator shaft for oscillating the last mentioned shaft.
8. In an operating mechanism for the agitator of a washing machine, a shaft for said agitator and means carried by the agitator shaft for oscillating said shaft, said means comprising a continuously rotating drive means, a clutch member below and a clutch plate above said drive means and adapted to form a clutching engagement 25 with the said drive means, an eccentric mounted on said plate, and link mechanism connected to said eccentric and to said shaft for oscillating the shaft and agitator.
9. In an operating mechanism for the agitator of a washing machine, a shaft for said agitator and means for oscillating said shaft, said means comprising a continuously rotating drive means, a 30 slideable clutch member below and a clutch plate above said drive means, a pin mounted on said clutch member, openings in said clutch plate 35 adapted to receive said pin whereby to form a clutching engagement with said drive means, and eccentric means connected to said clutch plate and shaft for changing the continuous rotation 40 to an oscillatory movement whereby to oscillate 45 the shaft and agitator.
10. In an operating mechanism for the impeller of a washing machine, a shaft for said impeller, and means for rapidly oscillating said shaft, said means comprising a continuously rotating drive means, eccentric means loosely mounted on said shaft, clutch means carried on the shaft and adapted to form a clutching engagement with said drive means and eccentric means, a segment connected to said eccentric means and oscillated thereby, and a pinion mounted on the shaft and meshing with said segment for oscillating said shaft and impeller. 50
11. In an operating mechanism for the agitator and wringer of a washing machine, comprising an agitator shaft, a wringer shaft, and means on said agitator shaft for continuously rotating the wringer shaft and for rapidly oscillating the agitator shaft.
12. In an operating mechanism for the agitator and wringer of a washing machine, comprising an agitator shaft, a wringer shaft, drive means on said agitator shaft for continuously rotating the wringer shaft, eccentric means associated with the drive means and agitator shaft for rapidly oscillating the last mentioned shaft, and a clutch for connecting and disconnecting the drive and eccentric means. 55
13. A power drive unit for oscillating the agitator shaft of a washing machine, comprising a continuously rotating drive means, and means for changing the continuous rotation into an oscillatory motion of desired amplitude in which the movement of the shaft is rapidly accelerated 10 to the mid-point of its stroke and then rapidly decelerated to the end of the stroke, said means being connected to the drive means and comprising a connecting rod reciprocated by the drive means, an arcuate arm connected intermediate 15 its ends to the connecting rod, one end of the arm being fixed and the other end free to transmit the motion given it by the connecting rod, a link pivoted at its one end to the free end of the arm and a member having its one end pivotally connected to the other end of the link and its other end fixed upon the shaft for transmitting the oscillatory motion and thereby oscillating the shaft through a desired arc and cycle of oscillation. 20
14. A power drive unit for oscillating the agitator shaft of a washing machine, comprising a continuously rotating drive means, and means for transforming the continuous rotation into an oscillatory motion of desired amplitude in which 25 the movement of the shaft is rapidly accelerated to the mid-point of its stroke and then rapidly decelerated to the end of the stroke, said means being associated with the drive means and comprising a connecting rod reciprocated by the drive 30 means, a cantilever connected to the rod intermediate its ends and fulcrumed at its one end with its other end connected to the agitator shaft in such manner as to oscillate the shaft through a desired arc and cycle of oscillation, 35 and clutch mechanism on the agitator shaft for connecting or disconnecting the drive and oscillating means. 40
15. In an operating mechanism for the agitator shaft of a washing machine, comprising a continuously rotating drive means, eccentric means for changing the continuous rotation of the drive means into an oscillating motion, a clutch slidably arranged on the agitator shaft for connecting the drive and eccentric means, and a system of levers so constructed and arranged 50 as to connect the eccentric means to the agitator shaft in such a manner as to produce a rapid acceleration at the beginning of and deceleration at the end of each stroke. 55

JOHN MIKULASEK.
